UNITED STATES PATENT OFFICE

2,233,456

REFRIGERATING APPARATUS

Lawrence A. Philipp, Detroit, Mich., assignor to Nash-Kelvinator Corporation, Detroit, Mich., a corporation of Maryland

Original application May 31, 1934, Serial No. 728,289. Divided and this application November 11, 1937, Serial No. 174,098

4 Claims. (Cl. 62—116)

5 My invention pertains to refrigerator compressor and evaporating units and more particularly to a non-frosting two temperature refrigerator cooling and freezing structure united with a compressor unit.

The present application is a division of my co-pending application Serial No. 728,289, filed May 31, 1934, for Refrigerating apparatus.

10 It is an object of my invention to provide a non-frosting refrigerator cooling structure which is especially effective and convenient for use in two temperature systems.

15 The invention itself, however, both as to its organization and its method of operation, together with additional objects and advantages thereof, will best be understood from the following description of specific embodiments, when read in conjunction with the accompanying drawings, in which:

20 Fig. 1 is a vertical sectional view taken transversely through a refrigerator cabinet provided with a unitary non-frosting two temperature cooling unit in accordance with my invention;

25 Fig. 2 is a sectional view taken on line 2—2 of Fig. 1;

Fig. 3 is a cross-sectional view taken on line 3—3 thereof;

Fig. 4 is a perspective view showing a partition member for enclosing a freezing chamber;

30 Fig. 5 is a vertical sectional view taken transversely through a refrigerator showing another embodiment of my non-frosting cooler unit installed in a refrigerator cabinet;

Fig. 6 is a sectional view on line 6—6 thereof;

35 Fig. 7 is a sectional view showing a cross-sectional view taken on line 7—7 thereof;

Fig. 8 is a detail view showing the finned cooling plate structure for cooling the food compartment;

40 Fig. 9 is a vertical sectional view taken transversely through a refrigerator cabinet showing a side mounted modification of the cooling unit structure;

Fig. 10 is a sectional view on line 10—10 thereof;

45 Fig. 11 is a cross-sectional view on line 11—11 thereof;

Fig. 12 is a sectional view taken through a refrigerator cabinet showing a modification of my invention comprising a secondary system; and

50 Fig. 13 is a diagrammatic view representing the cooperative relation of the various elements as interconnected in my two temperature refrigerating system.

55 Referring more specifically to Figs. 1, 2, 3 and 4 of the drawings the structure, as shown, comprises a refrigerator cabinet 1 of the usual heat insulating construction including a movable heat insulating closure member 2 which is supported on hinges 3 at one side of the cabinet in the usual

5 manner. A heat insulating wall 19 horizontally disposed between a food compartment 5 and a machine compartment 6 includes a removable portion 7 comprising a base mounting member on which the compressor machine unit and the associated elements are removably mounted in the cabinet. The machine unit comprises a compressor enclosed in a suitable hermetically sealed casing 12 and interconnected through suitable conduit means 13 with the usual condenser 14 10 for compressing and condensing the refrigerant. From the condenser 14 the refrigerant passes through a conduit 15 to a high side float valve 16 as will be more fully set forth subsequently. A fan 17 adjacent the condenser 14 circulates air therethrough and the machine compartment may be provided with vents in the usual manner. The compressor may be controlled to operate intermittently in accordance with the temperature conditions within the refrigerator cabinet by a 20 heat responsive switch in the usual manner.

In accordance with my invention the interfitting surfaces between the edges of the removable heat insulating base 7, and the adjacent partition or wall 19, are beveled whereby the weight of the 25 compressor machine thereon forces them into close fitting relation. A gasket 22 of yieldable material, such as rubber for example, is provided between the interfitting beveled surfaces to insure that a well sealed contact is established.

30 The food compartment 5 is cooled by finned defrosting cooling plates 24 which are suspended on suitable supports 25 from the lower side of the removable base member 7. Heat absorbing fins 26 are provided on the cooling plates 24 by securing channel shaped metallic strips 27 in intimate thermo conductive relation thereon in any suitable manner as by welding or soldering. The heat is carried away from the cooling plates by passing a refrigerant through coils of suitable 40 conduit secured thereto in heat conductive relation.

35 A portion of the food compartment space 5 within the cabinet is enclosed as a freezing chamber 30, by a partition member 31 which is permanently secured to the cabinet structure. The partition member 31 is preferably a sheet metal structure of substantially U shaped cross section closed at one end as shown in Fig. 4, and it is 45 preferably provided with a hard coating of vitreous enamel such as porcelain to present a pleasing appearance. Wide flanges 32 project laterally from the open edges of the partition member adjacent the open end of the U and are provided with holes 33 to receive screws or other fastening 50 means for securing the partition member permanently to the upper wall of the cabinet as shown in Fig. 1.

55 The partition member 31 is mounted directly beneath the compressor unit assembly, and the 60

wide flanges 32 along the sides of the permanently mounted partition member are provided with elongated slots 34 through which the cooling plates, depending from the removable machine base 7 may be readily inserted or withdrawn as the compressor unit is installed, or removed for shipping. The front openings of the freezing chamber 30 are defined by a front plate 37 which may be secured to lugs 38 projecting laterally from the front edge thereof. The front plate is preferably provided with a porcelain finish and is of pleasing contour having a peripheral curved or tapered flange or skirt to conceal the edge of the partition member and the adjacent cooling plates 24.

The freezing chamber enclosed within the porcelain partition member is cooled by freezing plates 41 which are secured together in parallel horizontally disposed relation and supported by suitable brackets 42 depending downwardly from the compressor base 7. The freezing plates comprise shelves for the reception of various articles or freezing trays 40, as shown in Fig. 6, and they are connected together by conduits 45 in order that refrigerant may be passed therethrough. Each of the freezing plates 41 may comprise a hollow chamber for the vaporization of the refrigerant, or each hollow plate may enclose a brine or other heat storing medium surrounding coils of conduit through which the refrigerant may pass in the usual manner.

It will be apparent that the freezing plate assembly within the permanently mounted porcelain chamber, together with the finned cooling plates adjacent the outer surface thereof may be readily removed as a unit with the compressor since they are all rigidly secured to the heat insulating machine base 7. When the unit is installed the freezing plates shelves 41 are lowered to their proper positions adjacent the openings in the front of the freezing chamber, the finned cooling plates 24 are inserted through the elongated slots 34 adjacent the outer sidewall surfaces of the freezing chamber and the weight of the compressor machine on the heat insulating base 7 causes its beveled edge surfaces to be wedged into tight sealed engagement with the adjacent beveled surfaces of the upper wall of the refrigerator cabinet.

The freezing plates 41 and the cooling plates 24 are operatively interconnected in series relation through suitable conduit means for the passage of refrigerant therethrough.

In accordance with another embodiment of my invention a finned cooling unit 61 is provided between the rear wall of the freezing chamber and the cabinet. By this arrangement the cooling plate is concealed behind the freezing chamber 62 and the space adjacent the sides of the freezing chamber may be advantageously utilized for storage purposes as shown in Figures 5, 6, 7, and 8. In this embodiment the porcelain partition member 63 enclosing the freezing member may be simplified by omitting the apertures in the lateral flanges and if desired the rear flanges may be entirely omitted or made relatively narrow. The front plate 64 is narrower and more useful storage space is available. The interconnection of the elements of the system is similar to that set forth previously and shown in Fig. 12, except that a single cooling plate is used. The cabinet is cooled by the finned cooling plate 61 and partly from the freezing chamber 62.

In another modification especially suitable for small refrigerators, my non-frosting two tem-

perature cooling unit may be mounted at one side of the cabinet thereby creating a compact structure as shown in Figs. 9, 10, and 11. In accordance with this modification a removable machine base 71 comprising a portion of the upper heat insulating wall 72 of the food compartment is disposed adjacent one side wall of the cabinet, which also serves as one of the enclosing walls of the freezing chamber 73. A porcelain partition member 74 which encloses the freezing chamber 73 comprises a structure of substantially L shaped cross section as shown in the sectional view in Fig. 9. Flanges 75 projecting laterally from the partition member are provided with apertures through which fastening means 77 may operatively engage the rear wall 78 of the cabinet to permanently support the partition member.

In this simplified construction the rear wall of the cabinet also closes the rear of the freezing chamber 73. The front edge of the partition member is provided with a lateral flange 81 for securing a front plate 82. A baffle plate 83 is also provided in parallel spaced relation to the side wall of the freezing chamber to control the air circulation and it is supported between the front plate 82 and the rear wall 78 of the cabinet to which it is secured by suitable flanges 84. A drip plate 86 is provided to drain the moisture from the cooling unit and it is supported in parallel spaced relation to the bottom of the freezing chamber 73 between the front plate 82 and the rear wall of the cabinet to which it may be secured by a flange 87 clamped by the fastening means 77 which also secures the partition unit 74. It is also desirable to provide an auxiliary drip deflecting strip 91 adjacent the side wall of the refrigerator under the freezing chamber. The adjacent edges of the drip strip 91 and the drip plate 86 are preferable turned downwardly to facilitate drainage into the usual drip pan 92 which is supported on a shelf 93 in the usual manner.

In this arrangement as in those previously described the freezing plates 41 are suspended from the removable machine base portion 71 of the upper cabinet wall by suitable brackets 42. A single finned cooling plate 24 is suspended from the machine base 71 by a suitable bracket member 97 between the baffle plate 83 and the side wall of the freezing chamber.

When the compressor and the associated elements mounted on the machine base are removed, the freezing plates 41 and the cooling plate 24 are withdrawn as a unit from the porcelain partition member 74 which is permanently secured to the cabinet. As shown in Fig. 10 the freezing plates 41 serve as shelves to support the freezing trays 40 within the freezing chamber and to provide a freezing compartment at the bottom of the chamber. The various elements of the compressor unit are mounted upon the heat insulated base in interconnected relation with the freezing and cooling elements in the cabinet.

In Fig. 12 I have shown an embodiment of my invention in which the cooling plate 101 for cooling the food compartment is mounted within the freezing chamber enclosed by the porcelain partition member 102. The outward surface of the cooling plate 101 is of flat smooth formation adapted to fit in close thermal abutting relation against the inside of the freezing chamber wall. The cooling plate may be lifted freely from the chamber with the removable condenser unit 75

assembly from which it is suspended. The cooling plate is connected to receive refrigerant from the condenser which also supplies the freezing plates in the freezing chamber as in the previous 5 embodiments. A sealed evaporator 104 is rigidly secured on the outside of the freezing chamber partition 102 opposite the cooling plate 101 and in close thermal association therewith.

The sealed evaporator 104 contains a volatile 10 refrigerant and comprises a secondary refrigerant system for absorbing heat from the food compartment.

As the heat within the food storage compartment vaporizes the refrigerant in the secondary 15 system evaporator 104 the vapor is condensed by the cooling plate 101 to which its latent heat of vaporization is transmitted and it is then dissipated by the associated system. The refrigerant condenser and compressor are removable 20 as a unit with the cooling plate 101 and the freezing plates 41 by simply lifting the structure upwardly from the cabinet.

In operation the refrigerant compressor unit 12 may supply liquefied refrigerant to the heat 25 absorbing elements through a system such as that diagrammatically represented in Fig. 13. The compressor pumps refrigerant vapor under high pressure into the condenser 14 and the condensed refrigerant from the condenser 14 passes through the float regulating valve 16 into the coils of the finned cooling plate 24 positioned adjacent one side of the freezing chamber. After the refrigerant expands through the coils of the cooling plate, an interconnected conduit carries it through a pressure reducing weight 30 valve 49 into the freezing plates 41 within the freezing chamber. The refrigerant then passes through the freezing plates 41 or coils therein provided in series relation through interconnected conduits 45. From the last freezing plate 35 of the series the refrigerant vapor is drawn through a suction line 53 to the compressor 12. The pressure reducing weight valve 49 through which the refrigerant passes between the cooling plate and the freezing plates serves to operate the respective freezing and cooling elements at different pressures and consequently at different temperatures in accordance with the selected or adjusted characteristics of the valve. The preferred 40 operating temperature of the cooling plate is such that it will defrost between operating cycles. In the embodiment of Fig. 12 the operating temperature of the cooling plate 101 is preferably such that the secondary evaporator 45 may defrost between cycles. This provides a non-frost element for cooling circulating air in the food compartment.

Although the connection of the cooling plates and the freezing plates in series relation provides 50 a convenient system it will be apparent that the respective cooling and freezing elements may also be arranged in parallel if desired. At times it may be desirable to connect the suction line to the cooling element and pass the high pressure refrigerant first into the freezing plates. A drip pan is provided on a shelf under the freezing chamber in the usual manner.

The arrangement and adjustment of the system to provide various temperatures within the 55 two temperature zones may be readily accomplished by suitably adjusting or selecting the various elements such as the pressure reducing valve and the compressor unit elements. I prefer to so select and adjust the elements of my

system that the cooling plates will operate at such temperatures that frosting is avoided or defrosting is accomplished automatically between operations of the compressor.

It will be seen that I have provided a non-frosting refrigerator cooling unit which may be advantageously utilized in combination with a two temperature system and a cabinet structure comprising a permanently mounted porcelain freezing chamber whereby the heat absorbing 10 elements normally mounted in the separate freezing and food storage compartments are conveniently removable with the compressor as a unit for shipping and installation, while the porcelain partition member enclosing the freezing chamber remains permanently mounted in the cabinet for protection. 15

While it is necessary for the purposes of illustration to describe the several disclosed forms of my invention in detail, it will be apparent 20 that the invention is not so limited and that other forms and applications thereof are embraced within the scope of the appended claims.

I claim as my invention:

1. Refrigerating apparatus comprising a cabinet, 25 an enclosure within said cabinet enclosing a low temperature zone including a vertical wall positioned in close proximity to a wall of the cabinet to provide an air cooling zone, heat absorbing means including a portion for maintaining low temperatures in said low temperature zone and a portion positioned adjacent said vertical wall for cooling circulating air to the desired temperature as it passes through said air cooling zone, and means for maintaining a 30 higher temperature in the heat absorbing portion which cools said circulating air. 35

2. Refrigerating apparatus comprising a cabinet, 40 an enclosure within said cabinet enclosing a low temperature zone including a wall positioned in close proximity to a wall of the cabinet to provide an air cooling zone, heat absorbing means including a portion for maintaining low temperatures in said low temperature zone and a portion positioned for cooling circulating air 45 to the desired temperature as it passes through said air cooling zone, and means for maintaining a higher temperature in the heat absorbing portion which cools said circulating air.

3. Refrigerating apparatus comprising a cabinet, 50 an enclosure within said cabinet enclosing a low temperature zone, including a wall positioned in close proximity to a wall of the cabinet to provide an air cooling zone, and heat absorbing means including a portion positioned in said low temperature zone for maintaining low temperatures in said low temperature zone and a portion positioned for cooling the circulating air to the desired temperature as it passes through said air cooling zone. 55

4. Refrigerating apparatus comprising a cabinet, 60 an enclosure within the cabinet enclosing a low temperature zone, heat absorbing means including a portion positioned in said low temperature zone and a portion positioned for cooling circulating air and extending vertically and parallel to a wall of said enclosure substantially from the top to the bottom of said wall and refrigerant flow control means for controlling the flow of refrigerant from one portion 65 to the other of said heat absorbing means. 70
